UNITED STATES PATENT OFFICE.

LAWRENCE SCHULLER, OF CHICAGO, ILLINOIS.

PLASTERER'S CORNER-BEAD.

SPECIFICATION forming part of Letters Patent No. 727,463, dated May 5, 1903.

Application filed April 17, 1902. Serial No. 103,344. (No model.)

To all whom it may concern:

Be it known that I, LAWRENCE SCHULLER, a citizen of the United States, residing at Chicago, in the county of Cook and State of Illinois, have invented certain new and useful Improvements in Plasterers' Corner-Beads; and I do hereby declare the following to be a full, clear, and exact description of the invention, such as will enable others skilled in the art to which it appertains to make and use the same.

My invention relates to a novel construction in a plasterer's corner-bead, the object being to provide a cheap and efficient device of this character which can be easily mounted; and it consists in the features of construction and combinations of parts hereinafter fully described and claimed.

In the accompanying drawings, illustrating my invention, Figure 1 is a detail horizontal section of a corner provided with a corner-bead constructed in accordance with my invention. Fig. 2 is a side elevation of my corner-bead. Fig. 3 is a transverse section of same on the line 3-3 of Fig. 2. Fig. 4 is a side elevation showing a modified form of construction. Fig. 5 is a section of same on the line 5-5 of Fig. 4.

My said device consists of a T-strip A, preferably made of sheet metal, the web of which is provided with a plurality of longitudinal slots B, said slots being enlarged at one end, as at C, and alternate slots having such enlargement C at opposite ends.

The fastening-strips D, each consisting of a flat strip of sheet metal bent at one end E to an angle of about forty-five degrees, are secured to said T-strip A at said bent end by means of offset tongues F, cut out of said end portions E, which are passed through the enlarged portions C of the slots B and are then inserted in the narrow portions of said slots, which they closely fit. The free ends of said fastening-strips are provided with

perforations G, adapted to receive nails or other fastening devices by means of which the bead is secured in position, as shown in Fig. 1.

In Figs. 4 and 5 I have illustrated a modified form of construction in which the web is provided with longitudinal slots not enlarged at one end and below said slots with recesses H half the length of said slots and below one end of same. The fastening-strips I are provided with Z-shaped ends adapted to enter the slots and with offset lugs J adapted to pass through said recesses and engage the lower edge of the web of the T-strip by moving the strip I longitudinally on said T-strip.

My said device is very advantageous, requiring a minimum amount of metal and permitting adjustment of the fastening-strips, this being essential where it is desired to secure the bead to a tile wall. It is also advantageous in that no tools are required to secure the fastening-strips to the T-strip.

I claim as my invention—

1. A plasterer's corner-bead comprising a T-strip provided in its web with a series of longitudinal slots enlarged at one end, and fastening-strips provided at one end with offset tongues adapted to enter said slots to secure said T-strip thereto.

2. A plasterer's corner-bead comprising a T-strip provided in its web with a series of longitudinal slots enlarged at one end, said slots being alternately enlarged at opposite ends, and fastening-strips provided at one end with offset tongues, said offset tongues being adapted to enter the enlarged portions of said slots and be engaged in the smaller portions of same to secure said T-strips.

In testimony whereof I affix my signature in presence of two witnesses.

LAWRENCE SCHULLER.
